PORTABLE PARTS CONTAINER
OR SIMILAR ARTICLE

Dennis G. Moore, 1312 Kathy Court,
Livermore, Calif. 94550

Filed Jan. 30, 1969, Ser. No. 15,572

Term of patent 14 years

Int. Cl. D3—99

U.S. Cl. D87—1

FIG. 1

FIG. 2

FIG. 5

FIG. 3

FIG. 4

FIG. 6

FIG. 1 is a front perspective view of a portable parts container or similar article, showing my new design;

FIG. 2 is a top plan view;

FIG. 3 is a front elevational view;

FIG. 4 is a right side elevational view;

FIG. 5 is a rear elevational view; and

FIG. 6 is a left side elevational view thereof.

The bottom, not shown, is plain and unornamented.

I claim:

The ornamental design for a portable parts container or similar article, as shown and described.
